UNITED STATES PATENT OFFICE

167,630

FIRE EXTINGUISHER

Charles K. Huthsing, Los Angeles, Calif., assignor
to The General Pacific Corporation, Los Angeles, Calif., a corporation of California

Application March 2, 1951, Serial No. 14,363

Term of patent 14 years

(Cl. D16—2)

To all whom it may concern:

Be it known that I, Charles K. Huthsing, a citizen of the United States, residing at Los Angeles, State of California, have invented a new, original, and ornamental Design for a Fire Extinguisher, of which the following is a specification, reference being had to the accompanying drawing, forming a part hereof.

Fig. 1 is a side elevational view of a fire extinguisher embodying my new design.

Fig. 2 is a top plan view thereof.

The dominant features of my design reside in the portions shown in full lines.

I claim:

The ornamental design for a fire extinguisher, substantially as shown and described.

CHARLES K. HUTHSING.
